UNITED STATES PATENT OFFICE.

BENJAMIN J. BROWN, OF GARDNER, MASSACHUSETTS.

CONVERTIBLE TABLE STRUCTURE.

Application filed June 2, 1928. Serial No. 282,412.

This invention is embodied in a structure adapted for use either as a table or as a fire-side screen, elements of the structure being a table top, an expansible and contractible top support including legs, and a coupling connecting the top with the support and organized to permit sliding and swinging movements of the top, so that it may assume a horizontal position above the support, to serve as a table top when the support is expanded, and to a vertical position beside the support when the latter is contracted, the top being thus adapted to serve as a screen, the elements of the structure being permanently connected so that the structure is indivisible when in an operative condition, and is convertible without detaching any element from another.

Of the accompanying drawings forming a part of this specification—

Figure 1 is a perspective view, showing a structure embodying the invention, converted into a table.

Figure 2 is a perspective view, showing the structure converted into a fireside screen.

Figure 3 is a fragmentary section on the planes indicated by line 3—3 of Figure 2, the top being in the position shown by Figure 2.

Figure 4 is a view similar to Figure 3, showing the top in different positions by full and broken lines.

Figure 5 is a view similar to Figure 3, the top being in the position shown by Figure 1.

Figure 6 shows the coupling in perspective, detached from the support and from the top, a portion of one of the runner members of the coupling being broken away.

The same reference characters indicate the same parts in all of the figures.

My improved structure comprises a flat top 12, and an expansible and contractible top support composed of two sections, each including a pair of legs 13, and a cross bar 14, connecting the upper ends of the legs. The cross-bar 14 of each section intersects and is pivoted to the cross-bar of the other section by a vertical pivot bolt 15, to permit expansion of the support, so that it has an enlarged leg base, as shown by Figure 1, and the contraction of the support, so that it has a contracted leg base, as shown by Figure 2, the expansion and contraction being caused by swinging movements of the sections relative to each other.

The structure comprises also a coupling

connecting the top with the support and organized to permit sliding and swinging movements of the top, so that it may assume either of the positions shown by Figures 1 and 2. An element of the coupling is a guiding base fixed to the intersecting portions of the cross-bars 14, and preferably formed as shown by Figure 6, the base being composed of a plate 16, perforated at 17 to receive the pivot bolt 15, and having spaced apart upwardly ears 18, provided with grooves 19. The other element of the coupling is an elongated runner slidably on the base, and interengaged with the grooves 19, to prevent sidewise movement of the runner out of engagement with the base.

The runner is composed of a longer member 20, fixed to the top 12 by fasteners 21, and a shorter member 22, connected by a hinge 23 with the member 20, said members having opposite longitudinal edges entering and slidably in the grooves 19. The members are engageable alternately with the guiding base, as best indicated by Figures 1 and 2.

When the support is expanded, the runner member 20 and the top 12 are supported in a horizontal position by the guide, as shown by Figures 1 and 5, so that the top 12 constitutes a table top, the member 20 being engaged with the groove 19, and horizontally supported by the guiding base, and the hinged member 22 being loose and out of engagement with the base.

When the support is contracted the runner member 22 is engaged with the grooves 19, and supported in a horizontal position by the base, as shown by Figures 2 to 6, the member 20 being out of the grooves and loose, so that said member and the top 12 attached thereto, are free to swing to a vertical position, causing the top to constitute a screen.

As above stated, the longitudinal edges of each of the runner members are interengaged with the grooves 19, so that the engaged member cannot be separated, by a sidewise movement, from the base. To prevent separation of the runner from the base by an endwise movement of the runner in either direction, I provide the outer ends of the runner members with stop shoulders 25. The shoulder on the runner member 22 is adapted to abut one end of the base, to limit the endwise movement of the runner in one direction, and the shoulder on the runner member 20 is adapted to abut the opposite end of the base, to limit the endwise movement of the runner

in the opposite direction. The runner and the top 12 are therefore practically inseparable from the top support and the base, and the structure is adapted to be quickly and conveniently converted to either of its uses.

The legs 13 may be braced by any suitable means. In this instance, the lower ends of the legs of each section are connected with each other by a bracing lower cross-bar 26, 10 the two cross-bars 26 intersecting each other and being connected by a pivot bolt 27. Any suitable means may be provided for limiting the contraction of the top support, so that the legs, when adjusted as shown by Figure 2, 15 will have a sufficiently stable, although contracted, leg base or bearing on a floor, to maintain the structure in an upright position.

The guiding base and the runner members are preferably composed of sheet metal, as 20 indicated by Figure 6, the stops 25 being transverse bosses. The runner members may be provided with longitudinal bosses 29, formed to bear on the top 12 and offset the longitudinal edges of said members from the 25 top, to accommodate the grooved portions of the base ears 18.

The upper edges of the cross-bars 14 have recesses 30 (Figure 1), providing raised portions on which the top bears when horizontally arranged, and depressed central portions accommodating the coupling.

The top 12 may have tongues 31, attached to its inner side and arranged to enter slots 32 in the cross-bars 14, when the structure is 35 a table.

I claim:

1. A convertible table structure comprising, in combination, a table top, an expandable and contractible top support composed of 40 pivotally connected sections including legs and intersecting cross-bars connecting the legs, and a coupling inseparably connecting the top with the support, and including a guiding base fixed to the upper portion of the support and maintained horizontally thereby, and an elongated runner slideable on and interengaged with the base, and composed of a longer member fixed to the top, a shorter member, and a hinge connecting said members, the members being engageable alternately with the base, the arrangement being such that when the longer member is engaged with the base, the top is supported horizontally 45 above the support, and the shorter member is loose, the structure constituting a table, and

when the shorter member is engaged with the base, the longer member and the top are loose, and permitted to swing to a vertical position beside the support, to convert the structure into a screen. 60

2. A convertible table structure comprising, in combination, a table top, an expandable and contractible top support composed of sections including legs and intersecting cross-bars connecting the legs, and a pivot bolt 65 connecting the cross-bars to permit the expansion and contraction of the support, and a coupling inseparably connecting the top with the support and including a guiding base secured in a horizontal position to the 70 support by said pivot bolt, and provided with grooved ears, and an elongated runner having longitudinal edges interengaged with said ears, the runner being composed of a longer member fixed to the top, a shorter 75 member, and a hinge connecting said members, the members being engageable alternately with the ears, the arrangement being such that when the longer member is engaged with the base, the top is supported horizontally 80 above the support, and the shorter member is loose, the structure constituting a table, and when the shorter member is engaged with the base, the longer member and the top are loose, and permitted to swing to a vertical position 85 beside the support, to convert the structure into a screen. 90

3. A convertible table as specified by claim 1, the runner being provided with stops at the outer ends of its members, adapted to cooperate with the base in limiting the sliding movements of the runner, to prevent the endwise removal of either member from the base. 95

4. A coupling for the top and top support of a convertible table structure, said coupling comprising a guiding base having grooved ears, and adapted to be attached to a top support with the ears extending horizontally, and an elongated runner having longitudinal edges interengaged with said ears, the runner being composed of a longer member adapted to be fixed to a table top, a shorter member, and a hinge connecting said members, the members being engageable alternately with the base, so that each may be horizontally 100 confined by the base while the other is loose. 105

In testimony whereof I have affixed my signature.

BENJAMIN J. BROWN.
